UNITED STATES PATENT OFFICE

2,613,713

SOFT SOAP DISPENSER

Noah F. Peebles, Odon, Ind.

Application February 28, 1949, Serial No. 78,792

1 Claim. (Cl. 146—61)

1

This invention relates to a soft soap dispenser and has for its primary object to separate from a mass of soft soap, a charge of soap and to extrude said charge of soap through a discharge opening.

Another object is to feed the mass of soft soap under pressure toward the soap severing and extruding means.

Still another object is to assure uniform separation of the charges from the mass of soap.

The above and other objects may be attained by employing this invention which embodies among its features a container for a plastic mass of soap, a bottom closing the lower end of said container, said bottom having an eccentric soap discharge opening therethrough, a rotor mounted in the container near the bottom thereof for rotation in one direction about the vertical axis of the container, said rotor having an annular row of spaced openings extending therethrough each having a leading edge and a trailing edge, an upwardly inclined soap severing blade carried by the rotor at the trailing edge of each opening for severing soap from a mass of soap contained in the container and moving soap so severed toward the bottom of the container, a downwardly extending flange carried by the rotor at the leading edge of each opening and engaging the bottom of the container for directing severed soap toward the soap discharge opening, and means extending through the bottom of the container and connected to the rotor for positively moving said rotor in a direction to sever soap from the mass of soap and to extrude the severed soap through the discharge opening.

In the drawings:

Figure 1 is a side view partially in section of a soft soap dispenser embodying the features of this invention.

Figure 2 is a bottom plan view of the soap dispenser illustrated in Figure 1, certain portions being broken away more clearly to illustrate certain details of construction.

Figure 3 is a horizontal sectional view taken substantially along the line 3—3 of Figure 1.

Figure 4 is a fragmentary enlarged sectional view taken substantially along the line 4—4 of Figure 2.

Figure 5 is a bottom plan view of the rotor, and

Figure 6 is a perspective view of the device showing it in use.

Referring to the drawings in detail a container 10 comprises a tubular body 12 having a bottom 14, and a removable cover 16. The cover 16 has

2

secured to its underside a compression spring 18 to which a follower 20 is connected, so that the follower will be yieldingly advanced toward the bottom 14 of the container 10. The bottom 14 of the container is provided with an axial opening 22, and formed in the container bottom adjacent its periphery is a soap discharge opening 24 through which soap is extruded during the dispensing operation. The container 10 may be provided with a suitable wall bracket 26 by which it may be connected to a suitable vertical support.

Extending axially through the opening 22 in the bottom 14 is an externally screw threaded bushing 28 onto the upper end of which is threaded a suitable nut 30, and interposed between the lower end of the nut 30 and the bottom 14 is a suitable sealing gasket 32. A shaft 34 extends axially through the bushing 28 and carries adjacent its lower end a ratchet wheel 36. The upper end of the shaft is provided with a rectangular extension 38 which is pierced to receive a cotter pin 40 by means of which the rotor to be more fully hereinafter described is removably held on the rectangular extension 38.

Clamped to the underside of the bottom 14 by the head of the bushing 28 is one leg of a channel shaped frame member 42 through which the shaft 34 extends, and rockably supported on the shaft 34 is a hand lever 44 to which is pivoted a pawl 46 which engages the teeth of the ratchet wheel 36 as will be readily understood upon reference to Figure 2. A compression spring 48 yieldingly holds the pawl in engagement with the ratchet wheel so that when the hand lever 44 is moved in one direction the pawl will be free to ratchet over the teeth of the wheel 36 in a conventional manner. Obviously when the lever 44 is moved in the opposite direction, the pawl will engage the teeth of the ratchet wheel 36 and cause the shaft 34 to be rotated. A suitable tongue 50 is carried by the web portion of the channel member 42 and is bent inwardly so as to extend into the path of movement of the teeth of the wheel 36 and arrest movement of the wheel during the period that the lever 44 is being moved in a direction to cause the pawl 46 to ratchet over the teeth of the wheel 36. It will thus be seen that the shaft 34 will be driven in but one direction with the oscillation of the hand lever 44.

A rotor designated generally 50 is mounted on the squared portion 38 of the shaft 34 and comprises a disk 52 which is provided near and around its periphery with a plurality of radially offset slots 54, said slots being spaced equidistant from one another with their inner ends equidis-

tant. A rotor designated generally 50 is mounted on the squared portion 38 of the shaft 34 and comprises a disk 52 which is provided near and around its periphery with a plurality of radially offset slots 54, said slots being spaced equidistant from one another with their inner ends equidistant.

tant from the center of the rotor, each having a leading edge and a trailing edge. The trailing edge of each opening 54 is provided with an upturned blade 56 which serves to sever soap from the underside of a mass of soap S contained within the container 10, and to extrude the severed soap downwardly toward the bottom 14 of the container. Depending from the disk 52 adjacent the leading edge of each opening 54 is a flange 58, the lower edge of each of which scrapes the bottom 14, and cooperates with the blade of the next adjacent opening 54 in extruding the soap severed from the mass S through the discharge opening 24. Formed axially in the disk 52 is a rectangular opening 60 which receives the rectangular extension 38 of the shaft 34 so that the disk 52 will be moved in unison with the motion of the shaft 34.

Formed in the disk 53 and entering through the periphery thereof is a radial elongated opening 62 carrying adjacent its trailing edge an upturned blade 64 which serves to sever soap from the body of soap S adjacent the periphery thereof and direct the severed soap into the space between the rotor 50 and the bottom 14 of the container 10. An elongated slot 66 is formed in the disk 52 near the center thereof and carried by the disk adjacent the leading edge of the slot 66 is a downwardly extending flange 68 which cooperates with the bottom 14 of the container 10 in deflecting soap which may find its way toward the center of the disk outwardly, toward the periphery of the disk, and secured to the underside of the disk 52 adjacent the trailing edge of the opening 66 is a curved deflector blade 70 which is connected to one of the flanges 58, and extends downwardly from the disk 52 for engagement with the bottom 14. This deflector plate 70 cooperates with the flange 68 in directing soap collected in the dispenser adjacent the axis thereof toward the periphery of the dispenser.

In the preferred form of the invention a suitable inwardly extending arm 72 may be secured to the side wall of the container 10 for engaging a mass of soap S contained in the container, and holding it against rotation relative to said container.

In use, a mass of soap S is introduced into the container through its upper end to rest on the rotor 50 of the dispenser. With the cover 16 in position on the container 10 it will be evident that the follower 20 will be yieldingly urged into contact with the top of the mass of soap S so that the mass will be forced under yielding pressure against the rotor 50. Upon oscillating the hand lever 44, the pawl 46 will engage the teeth of the ratchet wheel 36 to cause the shaft 34 to rotate in a direction to advance the blades 56 against the underside of the mass of soap S, so as to scrape soap therefrom and move it into the space between the rotor 50 and the bottom 14. As the rotor moves, the soap removed from the mass of soap S will be engaged by the flanges 58 and moved toward the discharge opening 24 in the bottom 14 of the container 10. The flange 68 and the deflector 70 will cooperate in moving any soap which may find its way toward the axis of the container outwardly toward the periphery of the rotor 50, and the blade 64 will engage the

underside of the mass of soap S so as to scrape the mass of soap adjacent its periphery. In this way the soap will be removed from the mass of soap S in a substantially uniform manner so that the bottom of the mass of soap S will remain substantially level at all times. Obviously the extruded soap moving through the discharge opening 24 may be caught in the palm of the hand as suggested in Figure 6, and the quantity dispensed may be regulated by the number of oscillations of the hand lever 44.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In a soft soap dispenser, a container for a plastic mass of soap, a bottom closing the lower end of said container, said bottom having an eccentrically disposed soap discharge opening extending therethrough, said opening having one side adjacent the periphery of the container, said opening extending radially less than one-half the distance to the center, a rotor plate mounted in the container near the bottom thereof for rotation in one direction about the vertical axis of the container, said rotor having spaced inwardly from and around the periphery thereof a plurality of slots the leading edges of which are tangential to a circle concentric to the center of the rotor, said slots being spaced equidistant from one another with their inner ends equidistant from the center of the rotor, adjacent slots being perpendicular to one another, an upwardly inclined soap severing blade carried by the rotor at the trailing edge of each opening for severing soap from a mass of soap contained in the container and moving soap so severed toward the bottom of the container, a downwardly extending flange carried by the rotor extending along the leading edge of each opening and engaging the bottom of the container for directing severed soap toward the soap discharge opening, the edge of said flange being substantially parallel to the plane of said rotor plate, and means extending through the bottom of the container and connected to the rotor for positively moving said rotor in a direction to sever soap from the mass of soap and to extrude the severed soap through the discharge openings.

NOAH F. PEEBLES.
